UNITED STATES PATENT OFFICE

146,466

DESIGN FOR A WALL FLOWERPOT HOLDER

Orin F. Evans, Cincinnati, Ohio, assignor to Evan G. Evans, Cincinnati, Ohio

Application February 1, 1946, Serial No. 126,144

Term of patent 7 years

(Cl. D35—3)

To all whom it may concern:

Be it known that I, Orin F. Evans, a citizen of the United States of America, residing at Cincinnati, in the county of Hamilton, State of Ohio, have invented a new, original, and ornamental Design for a Wall Flowerpot Holder, of which the following is a specification, reference being had to the accompanying drawing, forming part thereof.

Fig. 1 is a front elevational view of the wall flowerpot holder, showing my new design.

Fig. 2 is a side view of the same.

I claim:

The ornamental design for a wall flowerpot holder, as shown.

ORIN F. EVANS.
